CLAIM

The ornamental design for a drinking glass, as shown and described.

DESCRIPTION

FIG. 1 is a bottom prospective view of a drinking glass showing our new design;

FIG. 2 is a top prospective view thereof;

FIG. 3 is a front elevation view thereof;

FIG. 4 is a rear elevational view thereof;

FIG. 5 is a left side elevational view thereof;

FIG. 6 is a right side elevational view thereof;

FIG. 7 is a cross sectional view taken along line 7-7 of FIG. 4;

FIG. 8 is a top plan view thereof; and,

FIG. 9 is a bottom plan view thereof.
